NASAL AND AURAL SPECULUM

William J. Cameron, Chicago, Ill.

Application June 15, 1934, Serial No. 730,770

15 Claims. (Cl. 128—6)

The surgical instrument which I have devised is a speculum such as is utilized in inspecting, diagnosing, operating upon, and treating the nasal, aural and other cavities. I have provided the device with instrumentalities, so that it may be inserted into a cavity and by moving a control lever the jaws of the speculum may be opened to dilate the cavity to permit access to the inner membrane, tissues and other physical formations for inspection and treatment.

In this connection the specula jaws move towards and away from each other in parallel relation. I have provided a suitable pawl and ratchet mechanism associated with the operating lever whereby said lever may be moved backward and forward with ratcheting action or the pawl may be released to permit free movement of the lever without ratcheting action.

The specula jaws or members are automatically returnable to a normally closed or retracted position, and provide jointly a walled passageway of conical or tapered formation. Novel means are also provided for removably mounting the specula members on suitable pivoted arms whereby such members may be readily dismounted for cleansing and sterilizing. Numerous other advantages will be apparent to persons skilled in the art after my invention is understood.

Among the objects of my invention are the provision of an instrument of the kind described that is novel in construction, economical to manufacture, compact in arrangement and is dependable in performing the functions it may be called upon to do. I prefer to accomplish the foregoing objects and to carry out my invention in substantially the manner hereinafter described and as particularly pointed out in the claims, reference being herein made to the accompanying drawing that forms a part of this specification, in which drawing,

Fig. 1 is a front elevation of my improved surgical instrument showing the structure opened and with one of the specula members, in dotted lines, being dismounted.

Fig. 2 is a view similar to Fig. 1, on an exaggerated scale showing the device closed.

Fig. 3 is a back view of a fragmental portion of the instrument.

Fig. 4 is a top plan of a portion of the structure parts.

Figs. 5 and 6 are detail views, also enlarged showing different relative positions of the pawl and ratchet mechanism.

The mounting structure of the instrument consists of a hollow or tubular stub 10 that is pro-

vided with a bayonet-slot 11 extending inwardly from its lower edge to coact with a lateral pin 12 upon the upper end portion of a handle member 13 that is preferably an elongated cylinder. The pin and slot permits the head portion of the instrument to be readily removed from the handle. The upper end of the handle is inserted into the stub 10 and carries an angular miniature electric lamp or bulb 14 that is adapted to be moved up out of the handle above the stub to illuminate the portion under inspection or operation or may be retracted into the handle where it will be out of the way, such movement of the lamp or bulb being accomplished by a suitable slide (not shown) movable upon the exterior of the handle. Any suitable connection with an electric current may be made at the lower end of the handle (not shown) and electric conductors extend from the lower end of the handle to the retractable socket in which the bulb is mounted.

The parts of the instrument are mounted upon and carried by the hollow stub 10 upon the exterior wall thereof opposite the bayonet-slot. Integral with the stub there is a triangular shaped hollow casting 16, the front or outer portion of which is open, and has a flat flange 17 projecting laterally from one of its walls and flush or in the same plane as the outer edges of the side-walls of the casting 16. This flange has a segmentally shaped edge that is serrated to provide ratchet teeth 18 and the curve of this edge is an arc of a circle struck from the axis of the pivot for the swinging lever that carries the co-acting pawl as will later be described. There is a flat flange 19 on the side of the box-like casting opposite the ratchet flange, and said flanges together with the outer edges of the walls of the casting 16 being all in the same plane, provide a flat or plane area upon which the jaw carrying arms may rest or be moved.

A pair of sickle-shaped arms are movably mounted upon the smooth shank portion of a headed pivot screw 20 that is screwed into a threaded hole at the lower or apex end of the casting 16, such shank passing through the superposed or overlapped lower ends of the straight portions 21 of the arms.

One of the arms has an off-set portion (as at 21^a) so the arms lie in the same plane against the plane area above mentioned, and in order to maintain said arms normally adjacent or moved towards each other I provide a spring 22 that has its intermediate portion coiled about the screw 20 within the box-like casting 16 and the straight end portions of which spring cross

- each other and bear against lateral pins 23 on the respective arms, as seen in Fig. 3.
- The upper portions 24 of the arms are segmental or crescent shaped the curvatures of which are disposed so that when they are in normal position the two portions 24 jointly provide substantially a two part circle or split ring. These segmental portions 24 removably carry the specula members or split cone of the instrument, and to this end the outer edges of the segments 24 at midway their length are provided with shoulders 25 that have slots 26 at their inner corners that terminate in narrow slits 27 so that spring lugs 28 are thereby provided on diametrically opposite sides of segmental portions of the sickle-shaped arms.

Nasal, aural and similar specula are usually of a hollow tapered or conical shape but instead of using an integral hollow cone I split the cone axially to provide two semi-conical members 29.

The wide rear portions of these members jointly form a cylindrical base, and have small ears 30 diametrically opposite each other that project radially therefrom. Annular channels 31 are made in these base portions and transversely through the ears, such channels being of a depth and width to readily receive the segmental or curved portions 24 of the arms. Small cross-pins 32 are driven into the ears so that they bridge the channels and are in position to pass under the spring lugs 28 by entering the slots 26 and frictionally engage the walls of said slots. To mount a semi-conical specula member on an arm, the channel in the base of such member on one side of the lug and cross pin is engaged with the upper end of the segmental portion of the arm. The member is then given a rotative movement causing the pin to ride over the outer edge of segment until the pin reaches the spring lug 28 where it is pushed or forced into the slot 26. In order to remove the member the foregoing operation is reversed.

In order to move the arms away from each other against the action of the spring 22 I have provided suitable cam means actuated by a lever that preferably carries the pawl and associated mechanism cooperating with the ratchet teeth 18. The lever is an elongated bar 33 fulcrumed at one end on the shank of a wide-headed screw 34 that is threaded into a hole in the support and disposed between the adjacent edges of the straight portions of the sickle-shaped arms.

At its fulcrumed portion the lever bar 33 is provided with a wide enlargement 35 so that it spreads over quite an area of the arms 21 against which the enlargement rests, and by this engagement with the surface of the arms by the lever enlargement said arms are maintained in operative position but may be readily moved as desired.

The lever 33 extends across and beyond the arms and has its free outer end portion provided with an L-shaped backward or reverse bend or flange 33^a (Fig. 4) that provides a housing and guide for a pawl device 36 that is in the form of a rectangular block slidably mounted in the guide formed between the L-shaped flange 33^a and the adjacent body portion of lever 33. The parallel portions of the flange and lever are provided with alining longitudinally extending slots 38 and a headed guide-pin 39 is driven through these slots and the pawl block 36 with its unheaded end projecting a suitable distance beyond the rear surface of the longer arm of flange 33^a. The outer end of the pawl block has a recess to

seat a coiled expansion spring 40 that is interposed between the block and the shorter or lateral arm of the L-shaped flange 33^a and is maintained in position by engagement with a small pin 41 driven through said lateral arm.

A triangular shaped thumb-piece 42 having a wide thumb engaging lateral flange 43 is pivoted at its apex on a small screw 44 that is mounted on the inner end of the L-shaped flange 33^a, and said thumb-piece has a cut-away central portion through which the adjacent end of the pawl guide pin 39 protrudes.

The edge of the cut-away portion nearest the pin 39 is preferably a straight edge 45 that is obliquely disposed with respect to the pin and at 15 the upper inner corner, or upper end of the straight edge 45 there is an off-set recess 46 to permit free movement of the pin in the guide slots 38 when the lever 33 is moved downwardly to open the jaws or specula members. To ratchet 20 the lever in an upward or reverse direction, the thumb-piece is swung upwardly on its pivot causing the straight edge 45 to act as a cam against the pin 39 to move it slightly outwardly and continued upward pressure on the thumb-piece will cause the pawl to ride successively over the ratchet teeth 18 while the spring 22 will draw the sickle-shaped arms towards each other.

Occasionally, it may be found desirable to open 30 and close the arms and specula members without ratcheting and to this end I provide a pawl throw-off that is adapted to release the pawl in any of the respective positions of the lever arm 33.

A small irregular-shaped plate 47 has a tapered end portion that is pivotally mounted on screw 44 outside the thumb-piece 42. This throw-off plate is provided with an upstanding lug 48 by which it may be manually swung on its pivot and above the lug there are preferably two recesses 49 and 50, the latter of which is of such depth that it does not engage the pin 39 of the pawl while the other recess 49 acts as a holder so that when the throw-off plate is moved downwardly the pin will seat in such recess and hold the pawl out of engagement with the ratchet teeth. In the event the jaws have been opened, utilizing the ratchet mechanism, and thereafter it is desired to quickly close the jaws, the operator need only push downwardly on the lug 48 which will cause the pin to ride over the hump 51 between the recess and seat in the upper recess, thereby releasing the pawl from the ratchet teeth and permitting the jaws to close by the action of the spring 22.

What I claim is:—

1. A surgical instrument comprising a support, arms mounted thereon for movement toward and away from each other, cooperating specula blades carried by said arms, a swinging lever fulcrumed on said support, means embodying a cam actuated by said lever for moving said arms to separate said blades, a pawl and ratchet device controlling the movement of said lever, and means for releasing said device whereby to permit free movement of said lever.

2. A surgical instrument comprising a support, a pair of arms pivoted thereon, specula blades having channels in their base portions to receive portions of said arms, cross-members bridging said channels, and segmental extensions projecting from said arms which extensions are inserted in said channels back of said cross members.

3. A surgical instrument comprising a support, arms pivoted thereon for movement towards and

- away from each other, co-acting specula blades carried by said arms, a swinging lever fulcrumed on said support and extending across said arms between said blades and the pivot of said arms, 5 means embodying a cam actuated by said lever for moving said arms to separate said blades, and a pawl and ratchet device interposed between said support and said lever.
4. A surgical instrument comprising a support, 10 arms pivoted thereon for movement towards and away from each other, co-acting specula blades carried by said arms, a swinging lever fulcrumed on said support and extending across said arms between said blades and the pivot of said arms, 15 means embodying a cam carried by said lever and disposed between said arms for moving the latter to separate said blades, and a pawl and ratchet device interposed between said support and said lever.
5. A surgical instrument comprising a support, 20 having a plane area, flat arms pivoted adjacent their ends on said support and movable towards and from each other on said plane area, a flat lever fulcrumed intermediate its ends on said support and extending across said arms to maintain said arms against lateral movement, a pawl and ratchet device co-acting with said support and said lever, and oppositely shaped specula blades mounted on the free end portions of said 25 arms.
6. A surgical instrument comprising a support, 30 movable arms fulcrumed thereon, segmental extensions on said arms, semi-conical members carried by said extensions and having cylindrical base portions provided with annular channels into which said segmental extensions are removably inserted, and retainer pins disposed across said channels and engaged with adjacent portions of 35 said extensions.
7. A surgical instrument comprising a support, 40 movable arms fulcrumed thereon, segmental extensions on said arms, yieldable tongues on said extensions, semi-conical members carried by said extensions, cylindrical bases on said members having annular channels into which said extensions are removably inserted, and means on said bases adapted to engage said tongues whereby to 45 maintain said members against relative movement with respect to said arms and extensions.
8. A surgical instrument comprising a support, 50 elongated elements fulcrumed at their lower ends on said support a portion of each element being shaped to form a curved seat, said elements having open slots intermediate their ends, a hollow longitudinally split cone the sections of which are 55 removably mounted on said seats, and transverse pins on said cone sections that enter said slots to maintain said sections in position.
9. A surgical instrument comprising a support, 60 elongated elements fulcrumed at their lower ends on said support a portion of each element being shaped to form a seat, said elements having open slots intermediate their ends, a hollow longitudinally split cone the sections of which are 65 removably mounted on said seats, the bases of said cone sections being provided with annular channels to receive the portions of said elongated elements forming said seats, and pins disposed transversely across said channels and engaged 70 in said slots to removably retain said sections in position.
10. A surgical instrument comprising a support, 75 a pair of sickle-shaped arms pivoted at their lower ends on said support, a split cone mounted on the curved portions of said arms, means embodying a cam interposed between the straight portions of said arms, a lever connected to said cam means for operating the same to move the arms, pawl and ratchet devices respectively on said lever and said support, said pawl having a lateral pin, a thumb plate pivoted on said lever and having a portion movable into and out of 10 engagement with said pin, and a pawl release device adapted to engage and move said pin to maintain the pawl out of engagement with said ratchet.
11. A surgical instrument comprising a support, 15 oppositely disposed specula members having pivotal connection with said support, said members being movable towards and away from each other and in closed position adapted to form a passageway, and means for moving said specula members towards and away from each other in substantially parallel relation, said means including a pivotally mounted lever.
12. A surgical instrument comprising a support, 20 arms pivotally mounted on said support, oppositely disposed specula members carried by the respective arms, said members movable towards and away from each other and in closed position forming a passageway, a lever fulcrumed on said support, and means embodying a cam associated with said lever and arms 25 with respect to each other in substantially parallel relation.
13. A surgical instrument comprising a support, 30 arms pivotally mounted on said support, yieldable means urging said arms normally towards each other, semi-conical specula members removably mounted on said arms, said members movable towards and away from each other and 35 in closed position forming a passageway, a lever fulcrumed on said support, and means embodying a cam associated with said lever and arms 40 for operating the latter when said lever is moved.
14. A surgical instrument comprising a support, 45 arms pivotally mounted on said support, yieldable means urging said arms normally towards each other, semi-conical specula members removably mounted on said arms, said members movable towards and away from each other and 50 in closed position forming a passageway, a lever fulcrumed on said support, a pawl and ratchet device controlling said lever, a throw-off structure for disengaging the pawl from the ratchet, and cam means associated with said lever 55 and arms for operating the latter when said lever is moved.
15. A surgical instrument comprising a support, 60 having a flat surface portion, arms pivoted on said support and having flattened portions engaged with said flat surface, a reciprocable lever fulcrumed on said support and having a flat enlargement engaging said arms on the face thereof opposite the flat surface of the support whereby said arms are maintained and moved in edge alignment with each other, operating blades actuated by said arms, and means embodying a cam interposed between said arms and lever 65 for moving the latter.
